CLAIM

The ornamental design for an enamel on steel cookware with
see-through lid, as shown and described.

DESCRIPTION

FIG. 1 is a front-left perspective view of an enamel on steel
cookware with see-through lid showing my new design, the
bottom being flat and unornamented;

FIG. 2 is a top view of FIG. 1;

FIG. 3 is a front view of FIG. 1, the rear view being a mirror
image thereof;

FIG. 4 is a left end view of FIG. 1;

FIG. 5 is a right end view of FIG. 1;

FIG. 6 is a front view of a second embodiment of my enamel
on steel cookware with see-through lid, the rear view being
a mirror image thereof and the remaining views being the
same as the views of FIGS. 1-5 except for the difference in
pot size and the lack of a closed handle; and,

FIG. 7 is a front view of a third embodiment of my enamel
on steel cookware with see-through lid, the rear view being
a mirror image thereof and the remaining views being the
same as the views of FIGS. 1-5, except for the lack of a
closed handle.
